UNITED STATES PATENT OFFICE.

DAVID B. LEVY, OF NEW YORK, N. Y., ADMINISTRATOR OF LEO AMBERG, DECEASED, ASSIGNOR TO FRANCO-AMERICAN CHEMICAL WORKS, OF WOODRIDGE, NEW JERSEY, A CORPORATION OF DELAWARE.

STOPPER FOR BOTTLES.

SPECIFICATION forming part of Letters Patent No. 686,522, dated November 12, 1901.

Application filed June 22, 1901. Serial No. 65,562. (No model.)

To all whom it may concern:

Be it known that LEO AMBERG, deceased, late a citizen of the United States and late a resident of the city of New York, in the 5 county of New York and State of New York, did invent certain new and useful Improvements in Stoppers for Bottles, of which the following is a specification.

This invention relates to improvements in 10 stoppers for bottles, and especially to stoppers for bottles for containing and administering volatile liquids.

The object of the invention is to provide a 15 new and improved stopper which is simple in construction, closes the bottle absolutely tight, can be opened and closed easily and rapidly, and when so opened permits the internal pressure in the bottle to eject the liquid in a jet or stream with which the stopper 20 does not interfere.

In the accompanying drawings, in which like letters of reference indicate like parts in all the views, Figure 1 is a side view of the 25 improved stopper opened. Fig. 2 is a vertical sectional view of the same closed. Fig. 3 is a plan view of the same opened. Fig. 4 is a face view of the under side of the hinged cover-plate.

The bottle A has a neck B, and on the same 30 an externally-threaded sleeve C is secured.

The stopper is composed of a cylindrical or like block D, provided at its lower end with an internally-screw-threaded tubular extension E, which is screwed on the sleeve C. At 35 the top the block D is provided with a raised rim F, which is cut away for about half the circumference of the block, as at F'. In the inner surface of the remaining part of the raised rim a groove G is cut. A cover-plate 40 H of the diameter of the top of the block D is pivoted at its rim by a pivot-screw J to the upper surface of the raised rim F at one end of the same, so that the said cover-plate can be swung to one side from the upper end of 45 the block D, as shown in Figs. 1 and 3. A short neck K projects centrally from the under side of the cover-plate H and is provided with an annular flange L of such thickness and diameter that part of its edge can pass

into the groove G, as shown in Fig. 2. A 50 screw M, having a milled head O at its upper end and a socket P in its lower end, is screwed through a central screw-threaded aperture in the cover-plate H and neck K. A washer R, of vulcanized fiber or other like 55 or suitable substance, is placed into the socket P. Part of the flange L is cut off tangentially at the pivot-screw J, as at Q, to permit of swinging the cover-plate laterally. The upper end of the block is recessed and made 60 slightly conical to form a blunted point S, in which a capillary aperture T is formed, which communicates with the upper end of a tube V, which projects from the lower end of the block and into the tubular bottom extension E. 65

The operation is as follows: To close the bottle, the cover-plate H is swung over the upper end of the block D, the edge part of the flange L entering the groove G in the raised rim F, as shown in Fig. 2, and then the 70 screw M is screwed down for the purpose of firmly pressing the washer or packing R upon the blunted point S, whereby the capillary aperture T is closed tightly. The stopper cannot open accidentally, as the screw M 75 forces the edge part of the flange L against the top of the groove G, and thus holds the cover-plate in place. To open the bottle, the screw M is loosened sufficiently to raise the washer or packing R off the blunted point S, 80 and thereby the flange L is also loosened in the groove G and the cover-plate H can be swung to one side, as shown in Fig. 1, and the capillary opening T is now fully exposed and the contents of the bottle can be forced 85 as a fine jet by the pressure in the bottle through said capillary aperture. If the bottle is held horizontally, or nearly so, with the raised rim F at the top and the part F' toward the bottom, the cover-plate H swings 90 down automatically as soon as the screw M is loosened, and thus does not interfere with the spray or jet of liquid passing through the capillary aperture.

Having described the invention, what is 95 claimed as new, and desired to be secured by Letters Patent, is—

1. In a stopper for bottles, the combination

with a block having a capillary aperture, of a cover-plate pivoted on said block and a screw in said plate for closing the capillary opening, substantially as herein shown and described.

2. In a stopper for bottles, the combination with a block having a capillary aperture, and a semicircular, internally-grooved raised rim, of a cover-plate pivoted to said rim, a projecting part on the cover-plate, which enters said groove, and a screw in said cover-plate for closing the capillary aperture, substantially as herein shown and described.

3. In a stopper for bottles, the combination with a block having a recess in its top and a slight conical rise in the bottom of said recess, and a capillary aperture in the apex of said raised part, of a cover-plate pivoted to said block, and a screw mounted in said cover-

plate for closing the capillary aperture, substantially as herein shown and described.

4. In a stopper for bottles, the combination with a block having capillary aperture in its upper end, of a cover-plate pivoted to the upper end of said block to swing laterally in a plane parallel to that of the upper end of the block, a screw mounted in said cover-plate, and a washer on the inner end of said screw for closing the said capillary aperture, substantially as herein shown and described.

Signed at the city of New York, in the county of New York and State of New York, this 6th day of June, 1901.

DAVID B. LEVY,
Administrator of the estate of Leo Amberg.

In presence of—
OSCAR F. GUNZ,
GEO. E. CRUSE.
